UNITED STATES PATENT OFFICE.

WILLIAM GEORGE REYNOLDS, OF GRANDVIEW, MANITOBA, CANADA.

PRINTING MACHINE.

Application filed October 2, 1925, Serial No. 60,064, and in Canada October 13, 1924.

The invention relates to improvements in printing machines and an object of the invention is to provide a printing machine wherein the paper sheets to be printed are placed in a stack within the machine and are automatically fed to the platen and are withdrawn from the platen after the printing has been done thereon.

A further object of the invention is to provide a machine having an internal magazine for the stack of sheets to be printed and the platen thereof provided with means for effecting a suction blast to withdraw a sheet of paper from the stack and hold it on the platen during the entire printing operation, and further to provide the machine with means for automatically withdrawing the printed sheet from the platen, thereby clearing the printed sheet from the machine and permitting a further sheet to take its place on the platen.

A further object is to provide a construction which will cause the stack of paper to clear out of the road of the platen in the up-movement of the platen and will return the stack of paper to its initial position after the platen has come back.

A further object is to provide a table for supporting the stack of papers and means associated with the table for automatically raising the same, one sheet displacement each time a sheet is printed.

A further object is to provide a machine which is entirely automatic in its operation, it being only necessary to place the stack of sheets therein and to drive the machine, the feeding, printing and removal of the sheets being all done without requiring manual attention.

With the above more important objects in view the invention consists essentially in the arrangement and construction of parts hereinafter more particularly described, reference being had to the accompanying drawings in which:

Fig. 1 is a side view of the machine, the fly wheel being removed.

Fig. 2 is a front view of the machine.

Fig. 3 is a plan view thereof, the fly wheel and associated parts being removed.

Fig. 4 is a vertical sectional view at 4-4' Figure 3.

Fig. 5 is an enlarged detailed vertical sectional view through the jack screw employed and the gears associated therewith. 55

Fig. 6 is an enlarged detailed horizontal sectional view at 6-6' Figure 4.

Fig. 7 is an inverted plan view of the platen.

Fig. 8 is an enlarged detailed vertical sectional view at 8-8' Figure 7. 60

Fig. 9 is a perspective view showing one of the kickers for striking the edges of the papers, and also the operating mechanism therefor. 65

Fig. 10 is a perspective view showing the operating mechanism for the striker employed for striking the front ends of the papers.

Fig. 11 is a perspective view of the operating mechanism controlling the striker for striking the rear ends of the papers. 70

Fig. 12 is an enlarged detailed inverted plan view of the ratchet wheel and parts associated therewith. 75

Fig. 13 is an enlarged detailed vertical sectional view at 13-13' Figure 3.

Fig. 14 is a face view of the cam located at the rear side of the machine.

In the drawings like characters of reference indicate corresponding parts in the several figures. 80

The main frame of the machine presents similar opposing, spaced, vertically disposed, front and rear side plates 1 and 2 connected by suitably positioned cross webs 3 and 4, the lower end of the plates being formed to provide side legs 5 and 6 which can be permanently bolted as indicated at 7 to a supporting base. The side plates are each provided with opposing extensions 8 and 9 which carry an elevated cross shaft 10. The inner faces of the side plates are each provided with opposing, vertically extending tracks 11 and 11' and also with a comparatively wide vertically disposed, centrally positioned channel 12. 85 90 95

Between the side plates I locate a substantially rectangular carriage 13 which is provided with side wings 13' slidably received 100

within the channels 12 and the carriage is provided on the underside centrally with a downwardly extending boss 14 which is straddled by the formed ends 15' of a swinging arm 15, the arm being centrally positioned between the plates and having the outer end thereof rotatably mounted on the shaft 10. This arm is swung up and down in a manner later described, and in such movement shifts the carriage, there being sufficient clearance provided at 15' to allow of the vertical swinging movement of the arm, without striking the boss.

Above the carriage I locate a substantially rectangular table 16 which is fitted with corner lugs 16' which ride the inner faces of the tracks 11 and 11' and the table is supported centrally by a jack screw 17 which screw threads through a bevel wheel 18 located at the upper end of an internally screw threaded sleeve 18', also threading on the jack screw and rotatably mounted within the boss 14. Suitable bearings 19 are introduced between the bevel wheel and the face of the carriage. It will be observed that the sleeve extends beyond the boss for a purpose later described.

A shaft 20 is rotatably mounted in the carriage and has the outer end squared for the application of a hand crank (not shown) and the inner end is fitted with a bevel gear 20' operating through a suitable slot provided in the carriage and meshing with the bevel gear 18.

35 An integrally formed disc 21 and ratchet wheel 21' are secured to the projecting end of the sleeve and the disc is fitted with a circumferential channel which receives a ring 22, the ring being free to rotate in the channel and being provided with a lateral extension 22' which supports pivotally, a spring pressed ratchet 23 engaging the ratchet wheel. A rod 24 is pivotally connected to the ring extension and is adjustably attached to the side plate 2 as indicated at 24'. The arrangement is such that in the up and down movement of the arm 15, the ratchet wheel is rotated a preselected distance and in a direction such that the jack screw will rise, and in rising, raise the carriage. The amount which the carriage rises for each reciprocation of the arm 15 is equal to the thickness of the sheets of paper being printed in the machine, a stack of paper 55 embodying a considerable number of similar sheets, being placed on the carriage.

The upper ends of the plates 1 and 2 are provided with opposing bearings 26' which carry rotatably, a cross shaft 26 to which I attach the substantially rectangular platen 27. A gear wheel 28 is secured to the forward end of the shaft 26 and the crank 28 is secured to the rear end thereof, the crank being provided with an outstanding 65 crank pin 28' and the gear wheel with an

outstanding pin 28' aligned with the crank pin. The front plate 1 is fitted with a hangar 29' and the said plate and hangar support rotatably, a driving shaft 29 and the driving shaft carries a fly wheel 30 and a pinion 31, the pinion meshing continuously with the gear wheel 28. A hand grip 32 is attached to the fly wheel for manually rotating the same.

To the side plates 1 and 2 a pair of upwardly extending swinging side arms 33 and 33' are pivotally attached at 33' and these side arms carry the type bed 34 and the inking disc 35 and the arms are connected by a cross web 36. The side arms 33 and 33' are connected by a cross shaft 37', the ends of which support similar side carriers 37 and 37' for the inking rollers 38, the inking rollers being adapted to travel on the inner edges of the upper ends of the arms 33 and 33', over the type bed and over the inking disc. An inking device (not shown) is provided for inking the disc, but as this is commonly employed, I have not shown or described the same.

A link 39 is pivotally connected to the cross web 36 and to the arm 15, the arrangement being such that the in and out movement of the side arms, later described produces a down and up movement of the arm 15. The shaft 37' is connected by pitmen 40 and 40' to the pins 28' and 28'' respectively, such pitmen producing an in and out swinging movement of the arms 33 and 33' and parts carried thereby in the rotation of the shaft 26.

The side carriers 37 and 37' for the inking rollers are fitted with flanges 37'' and one of these flanges, in the present instance, is connected by means of a link 41 to the upper end of the side plate 1, the link being pivotally connected at 41' to the said plate and at 41'' to the flange.

The arms 33 and 33', and all the parts carried thereby, including the type bed, inking disc, inking rollers and roller carriers are all of ordinary construction, being commonly used on printing machines at present manufactured, and on this account a more detailed description of them is not herein given. Their movement, under the influence of the pitmen and links 41 is also the same as usual, the turning of the shaft 26 effecting the in and out swinging movement of the type bed and also the turning of the carriers to cause the inking rollers to travel up and down to ink the type or form and pass over the inking disc.

I might here explain that in printing machines, it is usual to stack the sheets adjoining the machine and feed them by hand into the machine or to attach an automatic feeder to the machine to automatically feed the sheets. According to my invention, however, the machine is designed to provide a

magazine for the stack of sheets and the sheets are picked off the stack by a suction draft associated directly with the platen, is held on the platen during the printing operation and is removed from the platen after the printing, by automatically operated fingers.

My device is not an automatic feeding attachment to a printing machine, but rather 10 a printing machine designed and constructed such that the automatic paper feeder is incorporated as a part of the machine.

As hereinbefore stated, the stack of papers is placed on the table and takes a position 15 between the table and the platen, which it will be observed has its face normally down as best shown in Figure 4 of the drawings.

The platen is operated in unison with the type bed 34 and to this I secure an upstanding bracket 42 permanently to the platen, the upper end of the bracket being pivotally connected by a pin 42' to the inner end of a link 43, the outer end of the link being rotatably mounted on the shaft 37*. The inner end of the link, receiving the pin, is slotted as indicated at 43' to permit of a short idle endwise movement of the link and the arrangement is such that in the in swinging movement of the arms 33 and 33', 25 30 the platen and type bed come correctly together in the usual manner to effect the printing of the sheet. The slot 43' permits of an idle movement of the link 43 as aforesaid to give the stack of paper, time to clear 35 away before the platen starts to rotate, and here it is pointed out that before the platen starts to swing back, the arm 15 starts to lower the table and consequently the stack of papers. The said slot also obviously permits 40 the platen to get back into this original position before the stack of papers has come back up to its original position.

It is very desirable, that at the instance, 45 the paper is being printed, between the type bed and the platen, that the platen be positively locked against rotation and to this end I provide a plurality of locking dogs 44 permanently secured to a cross shaft 45 rotatably carried by the upper ends of the side 50 plates 1 and 2, and these dogs, when locking the platen, are timed by a cam, to pass into and out of engagement with suitable shoulders indicated at 46 formed on the top side of the platen.

55 The forward end of the shaft 45 is provided with an upstanding crank 47 and the crank carries a roller 47' operating in a cam groove 47* formed on the inner face of the gear wheel 28. The shape of the groove is such that in the rotation of the gear wheel 28, the roller will swing the crank 47 and oscillate the shaft 45 in a manner which will cause the dogs to engage with the shoulders 46 and positively lock the platen momenta- 60 rily against movement during the interval

that the printing of the sheet is being actually done.

The cam groove is designed to move the dogs 44 clear of the shoulders immediately after the printing has been done and into 70 contact with the shoulders immediately preceding the printing impression being made.

The sheet of paper picked up by the platen from the top of the stack is raised to its position on the platen by air suction and is 75 held to the platen by air suction during the printing operation and up till such time that the printed sheet is to be removed from the machine by gripping fingers later described.

The method for effecting the air suction 80 at the platen is now described.

A suction air fan, indicated generally by the reference number 48, is mounted on the front side of the plate 1 and presents a pulley 48' which is connected by means of a belt 85 or such like 49' to a pulley 49 secured to the shaft 29. The fan will be accordingly operated when the fly wheel is rotated and when operated the suction of the said fan is adapted to effect a downward air draft through a pipe 50, swivably attached to the fan casing at 50', and having the upper end thereof slidably telescoped within the lower end of a further pipe 51 connected swivelly at 52 to a T-pipe 53 mounted on the underside of 90 the platen at one end. The ends of the T-pipe connect with spaced air tubes 54 and 54' embedded in the under face of the platen, said air tubes being provided with suitably spaced air holes 55. The ends of the air 100 tubes are telescoped over the end of the T-pipe and a filler block 56 is interposed between the air tubes and is attached to the platen by releasable screws 56'. Referring to Figure 8 it will be observed that the 105 tubes have inwardly extending flanges 55* which are adapted to pass between the filler block and the platen, the filler blocks actually holding the air tubes in place on the platen when the screws 56' are tightened up. 110

According to this arrangement I can vary the distance between the air tubes by utilizing different widths of filler blocks and telescoping the tubes on the T-pipe to accommodate the width of blocks used. This permits me to adjust my air tubes, depending on the width of paper used, from time to time. The tubes 50 and 51 are telescoped and the swivel joints are made to allow the tubes to follow the movement of the platen. 115

From the above arrangement, it will be obvious that when the machine is running, the fan will cause a suction of air inwardly through the holes 55, which suction draft is utilized to pick up and hold against the 120 platen, the uppermost sheet of the stack of paper.

The dog 23, the ratchet wheel 21' and jack screw 17 are all designed and operated such 125 that the table 16 will rise, each time a sheet 130

is printed, sufficiently far to make up for the thickness of the sheet removed, prior to printing the same. In other words, during each revolution of the shaft 26, the table is raised the thickness of one sheet by the jack screw.

The platen is provided with downwardly extending side flanges 57 and 57' having a depth the same as the depth of the tubes and 10 filler block, and the flange 57' is cut away centrally to provide an entrance passage for the gripping fingers, shortly described.

The gripping fingers are carried by the platen and are automatically operated to 15 swing in and grip the sheet of paper against the platen, this occurring during the interval that the table is moving down and prior to the initial swinging movement of the platen. Subsequently the fingers, while still gripping 20 the paper, turn with the platen and when the platen comes back to its initial position the fingers withdraw to remove the paper, this withdrawing movement occurring before the table has come up to its initial raised position 25 under the influence of the link 39 and arm 15. The gripping mechanism is now described.

Forwardly on the platen I mount rotatably, a comparatively short cross shaft 58 30 which is provided at the rear end with a crank 59 and a roller 59' and at the forward end with a crank arm 60 the crank arm being connected by a rod 60' to a swinging arm 61 pivotally connected at 61' to the front side of 35 the platen. The roller 59' rides the face of a cam 62 permanently secured to the rear end of the shaft 26, the roller being held into contact with the cam by a spring 63, the spring being attached, in the present instance, 40 to the crank arm 60 and the platen.

The cam is designed, in the rotation of the shaft 26, to cause the in swinging movement of the free end of the arm 61 towards the platen, this occurring before the platen is 45 rotated. Subsequently the cam produces no movement in the arm during the interval that the platen is swinging to printing position and returning, but the instant the platen returns to its initial position (and prior to 50 the final raising of the table) the arm 61 is swung out and this out swinging movement is utilized to withdraw the printed sheet. The details of the fingers used for gripping the sheet are now described.

55 To the underside of the arm 61 I secure permanently a bracket 64', the lower end of which terminates in an inturned finger 64 and associated with the finger 64 I provide a further finger 65 which is provided with 60 standing side arms 66, these arms being pivotally connected to the bracket at 66'. The upper ends of the arms 66 are connected by a cross bar 67 which is released and locked in two positions by a dog 68 located 65 at one end of a shaft 68' rotatably carried

by the arm 61. The other end of the latter shaft is supplied with a crank 69 which is connected by a flexible line 69' to the platen.

In the initial position of the parts as shown in the drawings, it will be seen that the dog is overlying the bar 67 and that the fingers are open. In the in swinging movement of the arm 61 as controlled by the cam 62, the arms 66 are brought into contact with the side of the platen, the platen entering the open space (see Figure 13) above the finger 64. The arms 66 being struck, causes the finger 65 to close and the fingers have at this time entered through the passage 57' in the flange 57' and are positioned so that they will grip the sheet of paper held against the platen face by the air suction. At the time the arms 66 are struck to cause the gripping of the paper by the fingers, the same movement of the arms 66 causes an out swing of 85 the bar 67, with the result that the dog 68 drops in behind the bar 67 and locks the fingers gripped. As before explained, the sheet gripped is held by the fingers until the platen returns and the instant it returns, the cam 62 operates to swing out the arm 61 to its initial position, this resulting in the withdrawal of the printed sheet from the platen and permitting of the uppermost sheet 90 of the stack to be sucked up against the face of the platen when the paper rises to its highest position subsequently.

When the arm 61 is reaching its outer position, the line 69' draws taut and in so doing rotates the shaft 68' to raise the dog 100 and unlock the fingers, the paper will then drop.

The air suction produces a more or less vibratory movement of the upper papers of the stack and it is desirable to provide means for striking or tapping the edges of the papers to keep them centred. This mechanism is now described.

At the rear side of the machine I locate a pair of rollers 70 which are carried at the 110 rear end of a bar 70', the bar passing through a vertical slot in the side plate 2 and being carried slidably in a bearing 71 secured to the carriage 13. The inner end of the bar is secured to a cross bar 72 and the cross bar has the ends thereof lengthwise slotted as indicated at 72'. The bar 70' is fitted with a number of ratchet teeth 73 and has the toothed part thereof passing through the lower slotted end of a vertical post 73' permanently secured to an adjusting plate 74 115 slidably mounted for in and out adjusting movement on the carriage. A ratchet 75 is pivotally connected in the slotted end of the post and engages the teeth 73 and is provided with a lever arm 75' which is connected by means of an operating rod 76 to a striker or tapper 77 in the form of a bell crank pivotally mounted for vertical movement in slots 78 and a coiled spring 78' nor- 120 125 130

mally holds the pin in the upper end of the slots.

According to this latter arrangement, it is possible for the striker to strike the platen without being damaged.

The rollers 70 are designed, in the up and down movement of the carriage, to ride over a hump 70^x located on the plate 2 and when riding over the hump will give the bar 70' an end kick which will produce a tapping action of the striker 77 against the edge of the paper, the spring 78' functioning also to return the striker after it has been moved by the hump. This striking obviously occurs twice each revolution of the shaft 26. At the opposite side of the stack of paper, to the striker just described, and also at the ends of the paper I locate similar strikers which are actuated in a similar manner to strike the edges of the top sheets. In Figures 9 and 10 I have shown the mechanism for operating the latter strikers.

On the carriage and in a location opposing the bar 72 I locate a bar 79 which is parallel to the bar 72 and has the ends thereof slotted and is fitted centrally with an outstanding arm 79' corresponding to the arm or bar 70'. This bar 79' also equipped with ratchet teeth operating on a dog carried by an upper standing post, and the post carries a striker actuated by the dog, the details of the parts and their operation being the same as that hereinbefore described.

The bars 72 and 79 are connected by parallel end bars 80 located beyond the ends of the stack of paper and these end bars are provided with slanting slots 81 which receive pivoted arms 82, the arms being pivoted to upstanding posts 83 corresponding to those 73'. The arms 82 are prevented from lateral displacement by guides 84 and 84' and the rods 85 for operating the strikers 77 have their lower ends looped around the arms 82.

According to this arrangement, when the bars 72 and 79 are side shifted, the bars 80 are end shifted and this end shifting movement is utilized to raise and lower the arms 82 and consequently cause the operation of the strikers 77. The posts, of which there are six in the present instance, are all adjustable on the carriage, the base plate carrying the post being fitted with a jam screw 86, the head of which operation in a T-slot 87 cut in the carriage plate. The posts all pass through suitable slots made in the table as do also the rods for operating the strikers.

What I claim as my invention is:—

1. In a printing machine in combination, a platen mounted to permit placement of a stack of paper sheets therebeneath, means for creating and maintaining a suction of air towards the face of the platen to draw the uppermost sheet of the stack towards the platen and subsequently hold the same

thereon, means for rotating the platen to printing position and for returning the same, means for shifting the stack of paper to clear the rotating platen and for returning the stack to its initial position and means for withdrawing a sheet of paper from the platen subsequent to the return of the same.

2. In a printing machine in combination, a platen mounted to permit placement of a stack of paper sheets therebeneath, means for creating and maintaining a suction of air towards the face of the platen to draw the uppermost sheet of the stack towards the platen and subsequently hold the same thereon, means for rotating the platen to printing position and for returning the same, means for shifting the stack of paper to clear the rotating platen and for returning the stack to its initial position and means for withdrawing the printed sheet from the platen subsequent to the return of the platen and prior to the return of the stack.

3. In a printing machine in combination, a table adapted to support a stack of paper sheets thereon, a platen above the stack of paper, means for rotating the platen to printing position, means for lowering and returning the table to clear the stack from the rotating platen, means for effecting a suction of air towards the face of the platen to draw the uppermost sheet of the stack against the face of the platen and hold the same thereon during the rotation of the platen and means for withdrawing the printed sheet from the face of the platen.

4. In a printing machine in combination, a table adapted to support a stack of paper sheets thereon, a platen above the stack of paper, means for rotating the platen to printing position, means for lowering and returning the table to clear the stack from the rotating platen, means for effecting a suction of air towards the face of the platen to draw the uppermost sheet of the stack against the face of the platen and hold the same thereon during the rotation of the platen, means for withdrawing the printed sheet from the face of the platen and means for automatically and intermittently raising the table to accommodate the decreasing height of the stack.

5. In a printing machine in combination, a form carrying type bed and a platen mounted to swing into printing contact, a table mounted within the machine and adapted to support a stack of paper sheets beneath the platen, with the uppermost sheet thereof normally opposing the platen, means for moving the table to permit the stack to clear the platen as it moves towards and returns from the form, means for effecting a suction of air towards the platen to draw the uppermost sheet of the stack to the platen and hold the same against the face thereof during the

printing operation and means for automatically withdrawing the successively printed sheets from the platen.

6. In a printing machine in combination, 5 a platen and a form carrying type bed mounted and operated to pass into printing contact, a table located within the machine and adapted to support a stack of paper sheets beneath the platen, with the upper- 10 most sheet of the stack positioned directly opposite the platen, means for effecting and maintaining a constant suction of air towards the face of the platen to initially draw the uppermost sheet of the stack 15 against the face of the platen and maintain it there during the printing operation, means for automatically lowering and raising the table to permit the stack to clear out of the path of travel of the moving 20 platen, means for automatically and intermittently adjusting the table to accommodate the diminishing height of the stack of paper sheets and automatically operated means carried by the platen for forcibly 25 withdrawing the printed sheet from the face of the platen.

7. In a printing machine in combination, a platen and a form carrying type bed mounted and operated to pass into printing contact, a table located within the machine and adapted to support a stack of paper sheets beneath the platen, the uppermost sheet of the stack being positioned directly opposite the platen, means for effect- 30 ing and maintaining a constant suction of air towards the face of the platen to initially draw the uppermost sheet of the stack against the face of the platen and maintain it there during the printing operation, 35 means for automatically lowering and raising the table to permit the stack to clear out of the path of travel of the moving platen, means for automatically and intermittently adjusting the table to accommodate the diminishing height of the stack of paper 40 sheets, automatically operated means carried by the platen for forcibly withdrawing the printed sheet from the face of the platen and means for momentarily locking the 45 platen against swinging movement during the interval that the platen and form are 50 in contact.

8. In a printing machine in combination, 55 a rotatably mounted platen having the face thereof normally down turned, an inwardly and outwardly swingable form carrying type bed, means for rotating the platen and for swinging the type bed so that they will 60 come into printing contact, a table located beneath the platen adapted to support a stack of paper sheet with the uppermost sheet of the stack normally opposite the face of the platen, perforated tubes carried by the face of the platen, means for effecting 65 a continuous suction air draft through the

tubes to draw the uppermost sheet of the stack against the face of the platen and maintain the same there during the rotation of the platen, means for automatically lowering and raising the table to clear the 70 stack out of the path of travel of the rotating platen, automatically operated gripping fingers carried by the platen adapted to grip the printed sheet held on the face of the platen by the air suction created and withdraw the same from the face of the platen, means for positively locking the platen momentarily against rotation during the interval that the platen and form are in contact and means for automatically and 80 intermittently adjusting the table to accommodate the varying height of the stack of paper sheets.

9. In a printing machine in combination, opposing side plates, an elevated cross shaft 85 suitably mounted in the side plates, a platen rotatably mounted on the shaft and having the face thereof down turned an inwardly swingable form carrying type bed pivotally carried by the plates, means for swinging 90 the type bed inwardly and outwardly, means for rotating the platen to cause the platen and type bed to come into printing contact each time the type bed swings in, means for automatically and momentarily locking the 95 platen against rotation during the interval that the type bed and platen are in contact, a carriage underlying the platen, a table carried by the carriage and serving to support a stack of paper sheets with the uppermost sheet of the stack being positioned opposing the face of the platen, means actuated by the swinging movement of the type bed adapted to raise and lower the carriage to clear the stack of paper from the path 100 of travel of the platen, said carriage moving prior to the platen and returning subsequently thereto, air tubes associated with the face of the platen, means for creating and maintaining a constant suction of air in the 105 tubes to draw the uppermost sheet of the stack to the face of the platen and hold the same thereon during the printing movement of the platen, automatically operated fingers carried by the platen adapted to grip the edge of the printed sheet of paper and forcibly withdraw the same from the face of the platen and subsequently release the sheet and means for automatically and 110 intermittently raising the table in respect to the carriage to accommodate the variation in height of the stack of papers on the 115 table.

10. In a printing machine, a platen, 120 means for holding a sheet of paper against the face of the platen by a suction of air and means for withdrawing the sheet of paper laterally from the face of the platen.

11. In a printing machine, a platen, 125 means for creating and maintaining a suc- 130

tion of air towards the face of the platen to draw a sheet of paper to the platen and hold the same thereon and means for withdrawing the sheet of paper laterally from the face of the platen.

12. In a printing machine, a platen, means for creating and maintaining a suction air draft towards the face of the platen, means for presenting sheets of paper suc-

cessively to the platen to be caught in the 10 air draft and held on the platen thereby, means for printing each sheet whilst held on the platen by the air draft and means for laterally withdrawing the successively printed sheets.

Signed at Winnipeg, this 25 day of September 1925.

WILLIAM GEORGE REYNOLDS.
